UNITED STATES PATENT OFFICE.

ANTOINE ISIDORE ODIER, OF PUTEAUX, FRANCE.

APPARATUS FOR STARTING INTERNAL-COMBUSTION ENGINES AND ALSO FOR OTHER PURPOSES.

1,339,411.

Specification of Letters Patent. Patented May 11, 1920.

Application filed August 11, 1919. Serial No. 316,719.

To all whom it may concern:

Be it known that I, ANTOINE ISIDORE ODIER, a citizen of the French Republic, residing at No. 64 Quai National, Puteaux, 5 Seine, France, have invented certain new and useful Improvements in Apparatus for Starting Internal-Combustion Engines and also for other Purposes, of which the following is a specification.

10 In my earlier patent application Serial No. 245,914 I have described an apparatus for starting internal combustion engines and for other purposes, wherein the casing enclosing the starting pulley is fixed on the 15 actual engine. In that arrangement the reaction of the starting strain is borne by the engine. For some purposes however it may be advisable that the entire starting apparatus shall not be fixed on the engine. 20 Such is more particularly the case when the starting apparatus is to be used for starting an engine mounted in an aeroplane or on the testing bench. For such applications it is absolutely necessary to have a support at 25 a point independent of the engine, for example on the ground.

The present invention has for its object improvements in the apparatus described in my aforesaid earlier patent application, de- 30 signed to constitute a removable apparatus capable of imparting rotary motion to any shaft, and more particularly to the shaft of an internal combustion engine, for effecting the starting of the said engine.

35 The apparatus thus modified, and constituting the improved apparatus, comprises the same essential elements as the starting apparatus described in my said earlier patent application, but the starting apparatus 40 proper is combined with devices designed to allow of adapting it instantaneously to the engine to be started, and to be disengaged from the said engine as soon as the latter is really started.

45 The accompanying drawings illustrate by way of example two constructional forms of this invention.

The first constructional form illustrated in Figures 1 and 2, is more particularly de- 50 signed for starting aeroplane engines, while the second constructional form illustrated in Figs. 3, 4 and 5 is designed for starting motorcar engines.

Fig. 1 is a vertical longitudinal section 55 of the first constructional form of the im-

proved apparatus. This figure shows the application of the apparatus for starting an aeroplane engine.

Fig. 2 is a side elevation of the said appa- 60 ratus.

Fig. 3 is a side elevation of the improved apparatus designed for starting motorcar engines.

Fig. 4 is a plan thereof.

Fig. 5 is a section of the apparatus on 65 the line I—I of Fig. 4.

Fig. 6 is a section of a detail on the line II—II of Fig. 5.

Fig. 7 is a diagrammatic front elevation 70 illustrating the application of the improved apparatus for starting a motorcar engine.

Referring to the constructional form shown in Figs. 1 and 2, the improved appa- 75 ratus for starting aeroplane engines comprises the following essential parts:—

In the casing 1 there rotates freely a shaft 2 on the inner end of which is fixed a grooved pulley 3. The other end of this shaft projecting outside of the casing is considerably swelled and is recessed; it car- 80 ries a certain number of driving studs 4 which project beyond the periphery of the shaft. A plate 5 closes the outer portion of the casing, and supports by means of a bearing 6 the inner end of the shaft 2. 85

A second plate (7) serves for the attachment by means of bolts, of a strut 8 which is thereby rigidly connected to the casing 1. The plates 5 and 7 are suitably curved in such a manner as to envelop and fix the 90 cylinder 9 of the starting apparatus. A piston, on one end of which is mounted a pulley 10, is adapted to work in the cylinder 9.

A cable engaging a lug 11 of the plate 7 95 makes half a turn around the pulley 10, then four turns around the pulley 3, and finally half a turn around the pulley 12 fixed on the strut.

To the end 13 of the cable there is at- 100 tached a spring 14 (preferably of rubber) and the end of this spring is attached in its turn to a fixed point 15 of the plates 5 and 7.

The spring 14 is inclosed in a tube 16 105 whose end 17 is made sufficiently wide to allow of the running portion of the spring to pass through, but is too small to allow of the passage of the link that connects the spring to the cable. A telescoping foot 18 110

capable of adjustment by hand, is connected to the upper end of the strut. It can be held in the desired position by means of an arm 19 that can be readily locked in position by means of a catch 20.

To the end of the cylinder 9 there is attached a pipe 21 leading to a tap 22 bolted to the strut 8. This tap has a screw thread on which there is adapted to be screwed by hand either a flask of liquid carbolic acid 23 as shown in Fig. 2, or a pipe communicating with a suitable pressure generator or reservoir.

On the end of the shaft 24 which is desired to be started, there is bolted a lug 25 which is cut in the form of a ratchet wheel having as many teeth as there are studs 4 on the shaft 2.

It is to be understood that the direction of the ratchet teeth must be so chosen as to insure that the shaft 2 shall drive the shaft 24 when the said shaft 2 is revolving in the direction of rotation which it is desired to impart to the shaft 24, and that when the shaft 24 is revolving in the desired direction and the shaft 2 is stopped, the pawls will automatically disengage the entire starting apparatus from the part or device to be started.

The operation of the improved apparatus is as follows:—Assuming that it is desired to start in the direction of the arrow shown in Fig. 2, an engine mounted on an aeroplane, the hub of the propeller of the aeroplane being indicated at 29, the starting apparatus must be brought up to the said hub in such a manner that the studs 4 of the shaft 2 shall engage with the teeth of the driving lug 25. The end 27 of the strut 8 is made to bear upon the ground and the telescoping foot 18 is adjusted so that the said foot bears likewise upon the ground. The whole arrangement is then locked in position by tightening the catch 20 of the connecting rod 19. Then on pressing the tap lever 22, a certain quantity of compressed gas will be admitted into the cylinder so as to push the piston and consequently the pulley 10. The effort received by this pulley is resolved into two equal tensile strains, namely one acting upon the end 11 of the cable and the other acting upon that portion of the cable which makes four turns around the pulley 3 and is connected to the spring 14.

After the piston has made a certain length of stroke which renders the cable of the spring taut, the friction upon the pulley 3 will be sufficient to cause the cable to carry with it the said pulley and consequently also the shaft 24 of the engine that is to be started.

If after some revolutions of the shaft 24 the engine is started, the inclined backs of the teeth of the lug 25 will force away

slightly the front portion of the entire starting apparatus which is thereby automatically disengaged from the engine. If, however, the engine has not started, the spring will return the piston slowly into its initial position; the tap 22 being so adjusted as to admit gas under pressure into the cylinder when the tap lever is pressed, and will allow this gas to escape immediately the pressure is removed from the said tap lever.

If by reason of a bad adjustment, after the first explosion, the engine starts to run backward, it will carry with it the pulley 13 in the reverse direction and thus exert a strong pull upon the cable that is wound around the pulley 10. The piston will thus be drawn slowly to the end of the cylinder, but at the moment it arrives there the catch 13 connecting the cable and the spring, will strike against the end 17 of the tube 16. The small residual tension of the spring at this moment is thus taken by the tube that incloses it, and since the end 13 of the cable is no longer taut, the friction of this cable upon the pulley 3 becomes *nil*, consequently any impulse which this pulley might still receive from the engine will cause the said pulley to revolve idly in the reverse direction.

It is to be understood that if the engine starts to run backward, the shock experienced by the starting apparatus will be transmitted to the strut whose end 27 bears firmly against the ground, in the same direction as if the engine had started properly. The result is that this back running of the engine will not in any way shift the starting apparatus. It will be merely necessary to press again upon the lever of the tap 22 to make a fresh attempt to start the engine.

It is advisable to arrange the parts of the starting device so that they all have a symmetry axis, because these arrangements allow of easily utilizing the apparatus, by merely reversing the parts to start engines in one or the other direction indiscriminately.

When the starting apparatus is employed for starting engines fitted with a starting crank, the apparatus acts directly upon the said crank. For this particular case the starting apparatus is constructed as shown for example in Figs. 3 to 6. The starting apparatus proper has the same characteristic features as the apparatus described in my said earlier patent application, but with the following modifications:—

Upon the cover 28 (Fig. 5) there is fixed a handle 29 by which the apparatus is grasped for manipulation. On the end of the cylinder 30 there is fixed a leaf spring 31 which can serve as an elastic point of support against the ground and fulfils the same function as the strut 8 of the hereinbefore described constructional form. The

free end of the shaft 32 of the starting apparatus carries a part by means of which the apparatus is connected to the starting crank 33. This part comprises (Fig. 6) a 5 collar 34 inside of which the axle of the crank is approximately centered by means of screws 35. A fork 36 allows the arm of the crank to pass through and also serves to drive the said arm. The screws 35 and 10 35' on the fork 36 are of course adjusted once for all for a given type of car. If it is desired to use the apparatus for another type of car, it is sufficient to alter the adjustment of the screws in order to adapt 15 the apparatus to the new starting crank; this is done in a moment.

The manner of using the improved starting apparatus is as follows:—The apparatus is grasped by means of the handle 29 20 and the collar 34 is engaged on the crank handle 33; the end of the cylinder 30 resting on the ground through the medium of the supporting spring 31 (Fig. 7). Then the operator with his free hand presses the lever 25 of the tap and thus connects the cylinder of the starting apparatus with a suitable reservoir containing compressed gas. By the action of the starting apparatus the crank is caused to make a few revolutions and the 30 engine is started.

Since the crank shaft ends in a clutch which opens automatically when the engine is started, the improved starting apparatus is gently forced back as soon as the engine 35 begins to revolve.

What I claim is:—

1. In an apparatus for starting an engine mounted in an aeroplane or motor car, the combination with a starter comprising a

cylinder, a piston member in the cylinder 40 arranged to be worked by pressure fluid, a pulley mounted on the piston member, another pulley mounted for turning the engine shaft, a spring attached to a fixed part and a rope attached at one end to a fixed 45 part adjacent the cylinder and at the other end to the spring and adapted to pass over the pulley for turning the engine shaft, of means for supporting said starter independently of the engine to be started, and means 50 for connecting said starter operatively and in a disconnectible manner to said engine, whereby said engine can be started without said starter being permanently carried by 55 said engine.

2. In an apparatus for starting an engine mounted in an aeroplane or motor car, the combination with a starter, comprising a cylinder, a piston member in the cylinder, arranged to be worked by pressure fluid, a 60 pulley mounted on the piston member, another pulley mounted for turning the engine shaft, a spring attached to a fixed part and a rope attached at one end to a fixed part adjacent the cylinder and at the other 65 end to the spring and adapted to pass over the pulley for turning the engine shaft, of means for supporting said starter independently of the engine to be started, and means for connecting said starter operatively and in an automatically disconnectible manner to said engine, whereby when 70 said engine is started said starter is automatically disconnected from said engine.

In testimony whereof I have signed my 75 name to this specification.

ANTOINE ISIDORE ODIER.
